UNITED STATES PATENT OFFICE

137,184

DESIGN FOR A PRECISION INSTRUMENT CASE

Sylvester A. Weyenberg, Hartland, Wis.

Application April 15, 1943, Serial No. 109,972

Term of patent 3½ years

To all whom it may concern:

Be it known that I, Sylvester A. Weyenberg, a citizen of the United States, residing at Hartland, in the county of Waukesha and State of Wisconsin, have invented a new, original, and ornamental Design for a Precision Instrument Case, of which the following is a specification, reference being had to the accompanying drawing, forming part thereof.

In the drawing:

Figure 1 is a perspective view of a precision instrument case embodying my new design, in closed position.

Figure 2 is a front elevational view thereof in open position.

Figure 3 is an edge elevational view of Figure 1.

I claim:

The ornamental design for a precision instrument case, as shown.

SYLVESTER A. WEYENBERG.
